UNITED STATES PATENT OFFICE.

THOMAS RAYMOND ARDEN, OF NEW YORK, N. Y.

COLLAPSIBLE ROD.

1,348,145.

Specification of Letters Patent.

Patented Aug. 3, 1920.

Application filed December 19, 1918. Serial No. 267,463.

To all whom it may concern:

Be it known that I, THOMAS RAYMOND ARDEN, a citizen of the United States of America, residing at New York city, in the 5 county and State of New York, have invented certain new and useful Improvements in Collapsible Rods, of which the following is a specification.

My invention relates to a collapsible rod 10 which may be used as a fishing rod, as a rod for cleaning gun barrels, as a cane and for other purposes to which a collapsible rod is applicable.

The object of the invention is to provide 15 a simply constructed and readily operable sectional rod which may be quickly set up or collapsed, and when in collapsed condition may be folded into a small compass without danger of any of the parts being 20 lost.

The invention consists essentially of a sectionalized rod, the several sections of which are held together by a flexible connector which may be controlled through the me- 25 dium of a terminal tension member.

The form in which I prefer to embody the characteristic features of my invention is shown in the accompanying drawing, wherein—

30 Figure 1 is a side elevational view of the device, the end of the rod being broken off; Fig. 2 is a plan view;

Fig. 3 is a plan view showing the position of the parts when the rod sections are released one from the other and in position to be folded together;

Fig. 4 is a side elevational view showing the device with the rod sections folded together, the front end section having a part 40 of its wall broken away to illustrate the manner in which the flexible connector is prevented from working out of such end section;

Fig. 5 is a side elevation of the rod in 45 completely extended position;

Fig. 6 is a side elevational view of the terminal tension member and the lever pivotally mounted thereon;

Fig. 7 is a substantially central sectional 50 view of the tension member of Fig. 6 with the lever omitted;

Fig. 8 is a fragmentary detail view illustrating the construction of the rod sections;

Fig. 9 is an elevational view partly in 55 section of the construction of a special form of outer end rod section; and

Fig. 10 is a sectional view partly in elevation of a detachable holder for a brush or like object when the device is to be used as a gun rod cleaner.

60

Before proceeding to a detailed description of the invention, it is desired to point out that when the device is in extended condition the parts thereof are rigid even though composed of sections, and this result 65 is obtained by causing the sections to interengage or partially nest one within the other, the flexible connector merely serving to hold the sections together under proper tension. The strain on the flexible connector is relatively light because of the firm engagement of the parts with each other.

70

Although the invention is susceptible of a great variety of uses, for simplicity of description I have herein shown it and will 75 describe it as being employed as a rod for cleaning gun barrels, although it is to be distinctly understood that the invention is not limited to such use.

In the drawing, 10 denotes a handle 80 which forms the support for the sectional rod. The handle is preferably channeled or trough shaped, comprising the base 11 and the lateral walls 12. Each of the lateral walls 12 is provided with a bi-part 85 slot the forward portion 13 being elongated and having straight edges, and the rear portion 14 being off-set in relation to the portion 13 and having its lower edge serrated or provided with notches as at 15. In the 90 drawing but one of the lateral walls 12 is shown slotted, although in practice both walls are provided with precisely similar aligned slots and notches.

The forward end of the handle terminates 95 in a socket 16 into which the rearmost of the rod sections, numbered from 17 to 20, is inserted.

All the rod sections may be alike in construction, each consisting of an elongated 100 hollow member, preferably tubular in form, having one end thereof 21 reduced or substantially conical, and at its other end a socket 22 so shaped as to snugly receive the portion 21 of the adjacent rod section.

105

Extending through the several rod sections is a flexible connector 23 which may be of any desired form, such as a chain, cord, or wire cable, the latter being the form shown in the drawing. The forward or outer end 110 of the connector 23 has an enlarged head 24 cast thereon or otherwise attached thereto

to prevent the cable from being drawn out of the rod section 20 when such cable is tensioned, as hereinafter described.

The cable extends rearwardly through the several rod sections and through the socket 16 into the handle 10 where it connects with the terminal tension member shown in detail in Figs. 6 and 7. This terminal tension member comprises, in the form shown, a casing 25 having about its periphery, either attached thereto or formed integrally therewith, a collar 26. Within the casing 25 is a coiled expansion spring 27 and at its rear end the wall of the casing 25 is formed as an inturned flange 28 constituting a stop for a perforated head 29 against which one end of the expansion spring 27 rests. The cable 23 is carried through the coiled spring 27 and through and beyond the perforated head 29 and is then knotted or provided with any other suitable enlargement such as 30 so that the cable is prevented from slipping through the terminal tension member.

Pivotedly mounted on the collar 26 is a suitably formed lever comprising a pair of shorter arms 31 and a pair of longer arms 32, connected by the web 32^a, the pivot for said lever being denoted by 33. The lever is channeled or trough shaped to permit the arms 32 connected by the web 32^a to span the rear part of the casing 25, and the lower end constituting the like arms 31 is bifurcated so as to allow the arms 31 to move freely in relation to the fore part of the casing 25. At its lower end each arm 31 is provided with a projecting stud or screw 34, the latter being operable in the slot sections 13 and 14 of the handle and in the notches 15.

The operation of the invention so far described is as follows: Assuming the rod to be in the extended position indicated in Fig. 5, the cone projection 21 of one rod section engages the socketed portion 22 of an adjacent section, and the cone projection 21 of the rearmost rod section 17 projects into the socket 16 in the handle. The flexible connector 23 is under suitable tension by the lever 31-32 having been turned downwardly about its pivot 33, and the studs 34 engaging in the oppositely alined notches 15. The position of the several parts is then that shown in Figs. 1, 2 and 5. If it be desired to collapse the device into the position shown in Fig. 4, the lever 31-32 is turned about its pivot 33 so as to raise the arms 32 (Fig. 6), thereby relieving the tension on the flexible connector 23 and permitting the studs 34 to be raised out of the notches 15 and the terminal tension member may then be slid forward in the handle 10, the studs 34 riding in the slot portion 13 whereby the flexible connector 23 is slackened. The several rod sections 17 to 20 are separated from each other by a very slight pull on each, and they may then be folded one upon the

other so as to assume the position shown in Fig. 4. If, now, it be desired to again move the parts into the position of Fig. 5, the rod sections 17 to 20 are permitted to fall toward the ground, and the terminal tension member is moved rearwardly in the handle 10 with the lever 31-32 raised as shown in Fig. 6, until the studs 34 are opposite the desired notches 15, thus drawing the rod sections close together, whereupon the lever 31-32 is turned downwardly tensioning the connector 23 as a result of which the rod sections 17 to 20 are all accurately alined and interengaged and firmly united to each other.

Excessive tension on the connector 23 is prevented by the coiled spring 27 in the cylinder 25. Should there be a tendency to too greatly tension the connector 23 the head 29 will be drawn inwardly and compress the spring 27 thereby relieving such excessive tension or strain on the connector 23. If the connector 23 should stretch, as it may do, after a considerable period of use, it may be shortened by simply making a new knot 30 and cutting off any excess length.

If the device is to be used for a special purpose such as a gun rod cleaner, I prefer to form the forward section 20^a as shown in Fig. 9 so as to be capable of receiving the brush holder of Fig. 10. Section 20^a is provided about midway of its length with a socket 35 and immediately adjacent thereto a slot 36 through its upper wall. Next to the slot 36 is a passage or opening 37 which passes completely through the tubular or hollow portion of the section 20^a. At its lower forward end the section 20^a is provided with an elongated slot 38 the front wall of which is beveled as shown at 39. The width of the passage 37 is greater than the width of the slot 36, while the lower portion of the socket 35 is somewhat larger than the upper portion 35^a thereof.

Referring to Fig. 10, the brush holder there shown consists of a bar or rod 40 having threaded into one end thereof an eye 41 to which the brush or swab for cleaning the gun barrel may be set. At its opposite end the bar 40 is reduced at 42 and set over the reduced portion 42 is a sleeve 43 capable of a limited sliding movement on said reduced portion 42. Within the sleeve 43 is a coiled spring 44 one end of which abuts against the end of the reduced portion 42, and the opposite end of which abuts against the inwardly set head 45 of the sleeve 43. The head 45 is centrally ori-ficed to receive the shank 46 of a bar which carries a ball or enlargement 47 at one end and has its opposite end 48 threaded axially into the bar 40. Intermediate its ends the shank 46 has a collar 49 fixed thereto against which the head 45 may abut. The sleeve 43 extends beyond the head 45 to form an an-

nular flange 43^a for a purpose to be described.

The brush holder of Fig. 10 may be attached to the section 20^a in the following manner:—The shank 46 with the head up is inserted upwardly through the passage 37 so that the brush holder assumes the position X indicated by the dotted lines in Fig. 9. Thereupon the brush holder is moved in the arc of a circle so that the shank portion 46^a which is reduced in diameter relatively to the rest of the shank, passes downwardly through the slot 36 and the ball 47 moves into the socket 35, the position being indicated in dotted lines at Y. In the arcuate movement the flange 43^a of the sleeve 43 will ride on the beveled edge 39 thereby compressing the spring 44, and when the ball 47 is completely seated in the socket 35 and the shank 46 is in axial alignment with the rod section 20^a the sleeve 43 will tend to move backwardly under the action of the coiled spring 44 and the projecting flange portion 43^a will engage the undercut edge 50 of the rod section 20^a thus providing a tight connection between the brush holder and such rod section. To release the brush holder from its engagement with the rod section 20^a the several operations just described are reversed, until the brush holder again assumes the dotted position X whereupon it may be drawn downwardly through the passage 37 and away from the rod section 20^a.

It is not my purpose to limit the invention to the details of construction shown and described, as the same may be varied by those skilled in the art without departing from the spirit of the invention as defined by the scope of the appended claims.

What I claim is:—

1. A collapsible rod, comprising a rod section, a support therefor, a flexible connector for connecting the rod section with the support, and pivotal means whereby said flexible connector may be tensioned.

2. A collapsible rod, comprising a plurality of interengageable rod sections, a support therefor, a flexible connector for connecting the rod sections with the support, and pivotal means whereby the flexible connector may be tensioned.

3. A collapsible rod, comprising a plurality of hollow rod sections, a support therefor, a flexible connector extending through the rod sections and connecting the same with the support, and pivotal means whereby the flexible connector may be tensioned.

4. A collapsible rod, comprising a plurality of rod sections each having a socket at one end and a corresponding projection at the other end thereof, a support for said rod sections, a flexible connector for connecting the rod sections with the support, and

pivotal means for tensioning said flexible connector to cause said projections to enter and engage said sockets.

5. A collapsible rod, comprising a plurality of rod sections, a support therefor, a flexible connector for connecting the rod sections with the support, and a pivotally mounted lever attached to said connector and operable in said support for tensioning and untensioning said connector.

6. A collapsible rod, comprising a plurality of rod sections, a support therefor, a flexible connector for connecting the rod sections with the support, a yielding member to which one end of the connector is attached, and means acting on said yielding member to tension and untension said connector.

7. A collapsible rod, comprising a plurality of rod sections, a support therefor, a flexible connector for connecting the rod section with the support, a yielding member in the support to which one end of the connector is attached, and a lever for actuating said yielding member to tension and untension said connector.

8. A collapsible rod, comprising a plurality of rod sections, a support therefor, a flexible connector for connecting the rod sections with the support, a spring-pressed member in the support to which one end of said flexible connector is connected, and a pivotally mounted lever for actuating said member to tension and untension said connector.

9. A collapsible rod, comprising a plurality of rod sections, a support therefor having serrated slots in its walls, a flexible connector for connecting the rod sections with the support, and means in the support engageable with the serrations in the slots therein for tensioning said connector.

10. A collapsible rod, comprising a plurality of rod sections, a support therefor having serrated slots in its walls, a flexible connector for connecting the rod sections with the support, a pivotally mounted lever operable in said support for tensioning and untensioning said connector, and means carried by said lever for engaging the serrations in the slots.

11. A collapsible rod, comprising a plurality of rod sections, a support therefor having serrated slots in its walls, a flexible connector for connecting the rod sections with the support, a casing in said support having a spring pressed movable head at one end thereof, one end of said connector being connected to said head, a lever pivotally mounted on said casing and adapted to tension and untension said connector, and projections on said lever adapted to engage the serrations in said slots.

12. A collapsible rod, comprising a support having a socket, a plurality of hollow

rod sections each thereof having a socket at one end and a corresponding projection at the other end thereof, a spring pressed member in said support, a flexible connector extending through said rod sections and having one end connected to said member, and a pivoted lever adapted to actuate said member to tension said flexible connector and cause engagement between said projections and said sockets.

13. The combination with a rod section having a socket intermediate its ends, a slot adjacent said socket and a passage adjacent said slot, of an article holder comprising a shank for movement through said passage and slot, said shank having an enlarged head adapted to be seated in said socket, and a yielding member partially inclosing said slot

and engageable with the end of said rod section.

14. The combination with a rod section having its forward end undercut and having a socket intermediate its ends, a slot adjacent said socket and a passage adjacent said slot, of an article holder comprising a shank for movement through said passage and slot, said shank having an enlarged head adapted to be seated in said socket, and a spring pressed sleeve adapted to releasably engage the undercut end of said rod section.

In testimony whereof I have affixed my signature in presence of two witnesses.

THOMAS RAYMOND ARDEN.
